UNITED STATES PATENT OFFICE

ARTHUR B. PAUND, OF CHICAGO, ILLINOIS

DOOR BUCK ANCHOR

Application filed April 19, 1927. Serial No. 184,940.

This invention relates to means for securing the vertical frame member of a door or other device to a partition wall formed of tile or like material. Devices of this character are commonly referred to as buck anchors or door buck anchors.

It is common in forming walls or partitions to place the tile or blocks one upon the other with mortar or other cementitious material between the blocks and at the end of the wall, as where a doorway occurs, to secure to the tile or blocks a vertical member usually of wood and commonly referred to as a buck or door buck.

These partitions are formed of different types of tile, as the cellular terra cotta tile and the plaster tile commonly referred to in the trade as macholite or pyrobar.

The object of the present invention is to provide a simple, light and inexpensive buck anchor which may be easily applied to walls formed either of terra cotta tile or plaster tile and which will act firmly to secure the door buck to the edge or end of the wall.

One of the features of the invention is a buck anchor so formed of sheet material that a part of the body portion of one anchor is cut or formed of the material removed from between the outwardly extending legs of another anchor.

Another feature of the invention resides in the provision of an anchor of sheet material having downwardly extending spurs or lugs, one of which is adapted to engage back of one of the transverse webs or partitions when applied to a terra cotta tile, and both of which are adapted to be driven into the upper surface of a plaster tile when employed therewith.

A still further feature of the invention resides in the proportions and arrangement whereby the forward end of the body portion of the anchor is spaced from the end wall of a terra cotta tile so that a tie or bond of mortar may extend between the end of the anchor and the end wall of the tile, acting more firmly to secure the anchor against lengthwise movement on the tile.

Other features and advantages will appear

from time to time as the description of the invention progresses.

It is believed the invention will be understood most readily from a detailed description thereof taken in connection with the accompanying drawings, in which:

Fig. 1 is a perspective view of a portion of a terra cotta tile associated with a portion of a door buck and showing the anchor of the present invention applied thereto;

Fig. 2 is a similar view, but shows a rectangular door buck secured to a plaster tile by means of the anchor of the present invention;

Fig. 3 is a perspective view of the anchor detached;

Fig. 4 is a side view of a wall having the door buck secured thereto by buck anchors;

Fig. 5 is a sectional view longitudinally of a terra cotta tile and buck, such as seen in Fig. 1, showing the manner in which the rear or larger spur of the anchor is positioned back of the first web or partition of the tile; and

Fig. 6 is a section viewing the tile and anchor from the right in Fig. 5.

Referring now to the drawings, in which like reference characters indicate the same parts in the several views, 10 indicates a door buck having therein the channel or groove 11. Extending into the groove 11 is one end or edge of the terra cotta hollow tile 12. The anchor 13 (Fig. 3) comprises the generally rectangular body portion 14 and the downwardly or laterally turned side wings 15. The wings 15 extend beyond the end of the body portion 14 to provide a pair of securing legs 16. Each of the legs 16 is provided with a plurality of openings 17, through which nails or other devices may be inserted to secure the anchor to the door buck.

The body portion 14 of the buck is centrally cut away, as indicated at 18, the pair of spurs 19 and 20 being provided as clearly shown in Fig. 3. It will be noted that the spur 20 is broader or larger than the spur 19.

Referring now to Fig. 1, it will be noted that the anchor is applied to the tile 12 with the wings 15 on opposite sides of the tile and with the larger spur 20 positioned in engage-

ment with the web or partition 21 of the tile. When used with terra cotta tiles, such as shown in Fig. 1, the spur 19 is without function.

- 5 Referring to the drawings, it will be noted that the rear end of the anchor has an arcuate projection 22 which is cut from the arcuate cut away portion 23 of the next anchor in the process of manufacturing. Referring 10 now to Fig. 1, it will be seen that the cut away portion 23 operates to provide an opening or space 24 between the end of the anchor and the end wall 25 of the tile. In the process of laying the partition or wall, mortar or 15 cement is placed upon the upper edge of the tile and a portion thereof will extend down through the opening 24; thus acting more firmly to secure the anchor against endwise displacement in the wall.
- 20 In applying the anchor to the wall, the legs 16 will preferably be turned outwardly at an angle so as not to engage the buck 10. After the wall has been laid, the legs 16 are bent into engagement with the buck 10 and 25 secured thereto by means of the nails or other devices 26 passing through the openings 17. In order firmly to secure the anchor in place, the ends of the legs 16 may be bent about the corner of the door buck 10, as shown in dotted 30 lines in Fig. 1, a securing device being passed through the end hole in the leg in an obvious manner.

It is, of course, understood that the anchors 35 13 will be placed between the layers of the tile, as clearly indicated in Fig. 4. It is optional how many of the anchors are employed. They may be provided at each course or joint between the tiles or less frequently as seems expedient. It is clear from 40 the structure thus far described that when the anchor is built into the wall, it is prevented from sidewise displacement by means of the wings 15 and is held against endwise displacement in an outward direction by 45 means of the lug or spur 20 engaging the partition 21 and also by means of the tie or bond or plaster which extends into the opening 24.

It will be noted that the point of attachment of the leg 16 to the body portion of the anchor is somewhat removed from the edge of the buck 10; thus permitting the buck to be more firmly secured to the wall without lost motion, than would be possible if the 55 connecting portion 27 extended substantially at right angles to the face of the tile.

In Fig. 2 a rectangular door buck is shown secured to a plaster tile 29, such as macholite or pyrobar, by means of the anchor of the 60 present invention. In applying the anchor to a plaster tile, the wings 15 are positioned on opposite sides of the tile with the outer end of the anchor slightly removed from the outer edge of the tile. The upper surface of 65 the anchor is then struck a slight blow or

blows, as with a trowel, and the spurs 19 and 20 are thus forced into the upper surface of the plaster tile. A layer of mortar or other cementitious material is then spread over the upper surface of the anchor and tile and the 70 next tile is placed thereon in an obvious manner. The plaster and weight of the tiles above operate firmly to hold the spurs 19 and 20 in the tile to prevent lengthwise movement of the anchor; while lateral movement 75 is prevented by means of the wings 15. The securing of the anchor between the plaster tile is made very secure by reason of the bond of mortar or cement between the tiles through the opening 18 in the anchor. The legs 16 of the anchor are secured to the buck 28 by means of the securing devices, as nails 26, in the same manner as described in connection with Fig. 1.

It is obvious that the terra cotta tile 12 of Fig. 1 may be applied to a door buck, such as the rectangular buck 28 of Fig. 2 and also that the plaster tile 29 may be used in connection with a channel door buck, such as the buck 10 of Fig. 1.

It is, also, obvious that applicant has provided a buck anchor which may be used equally as efficiently in either a terra cotta tile partition or wall or with a plaster tile structure. It is, also, obvious that many minor 95 changes in the details of the structure may be made without departing from the spirit of the present invention. The invention should, therefore, be limited only by the scope of the appended claims.

Having thus described my invention, what I claim is new and desire to secure by Letters Patent of the United States is:

1. In a buck anchor, a substantially flat plate adapted to be inserted between the wall blocks or tiles along with the mortar between the said blocks, the said plate having a cut-away portion centrally thereof, a spur formed from said cutaway portion and bent downwardly into a plane at substantially right angles to the plane of said plate, said spur being arranged to be positioned back of the first transverse partition of a terra cotta tile or to be embedded in a plaster tile, flanges at the opposite sides of said plate extending downwardly at substantially right angles thereto and adapted to engage the opposite sides of the block or tile in the wall, and flexible legs extending from one end of said plate adapted to engage and to be secured to the opposite sides of the buck, said legs being formed as continuations of said flanges.

2. In a buck anchor, a substantially flat plate adapted to be inserted between the wall blocks or tiles along with the mortar between the said blocks, the said plate having a cut-away portion substantially centrally thereof, spurs formed from said cutaway portion and bent downwardly into a plane at substantially right angles to the plane of said plate, one

of said spurs being arranged to be positioned back of the first transverse partition of a terra cotta tile and both of said spurs being adapted to be embedded in a plaster tile, flanges at the opposite sides of said plate extending at substantially right angles thereto and adapted to engage the opposite sides of a block or tile in the wall, and legs formed as continuations of said flanges extending from one end of said plate adapted to engage and to be secured to the opposite sides of the buck.

3. In a door buck anchor, a substantially flat plate adapted to be inserted between the tiles or blocks in a wall, spurs punched from said plate and extending at substantially right angles thereto, flanges at the opposite sides of said plate and bent at substantially right angles to the plane thereof, the said flanges extending beyond the end of said plate to form legs adapted to engage and be secured to the opposite sides of the door buck, the said flanges extending only a portion of the length of the said plate, whereby the legs of one anchor are formed of the material at the sides of the next anchor at the end of the said flanges.

In testimony whereof I have signed this specification.
